UNITED STATES PATENT OFFICE.

MATTESON T. KOCH, OF NEW LISBON, WISCONSIN.

END-GATE FASTENER.

SPECIFICATION forming part of Letters Patent No. 617,104, dated January 3, 1899.

Application filed February 23, 1898. Serial No. 671,341. (No model.)

To all whom it may concern:

Be it known that I, MATTESON T. KOCH, a citizen of the United States, residing at New Lisbon, in the county of Juneau and State of Wisconsin, have invented a new and useful 5 End-Gate Fastener, of which the following is a specification.

The invention relates to improvements in end-gate fasteners.

10 The object of the present invention is to improve the construction of end-gate fasteners and to provide a simple, inexpensive, and efficient device adapted to be readily applied to a wagon-body to dispense with a rod running through the sides thereof and capable of firmly holding a wagon body or box together and of taking up the wear of the parts to prevent them from becoming loose.

15 The invention consists in the construction and novel combination and arrangement of parts, as hereinafter fully described, illustrated in the accompanying drawings, and pointed out in the claims hereto appended.

20 In the drawings, Figure 1 is a perspective view of an end-gate fastener constructed in accordance with this invention and shown applied to a wagon-body. Fig. 2 is an end elevation, partly in section, showing the position of the parts when unlocked. Fig. 3 is a horizontal sectional view, the parts being arranged as shown in Fig. 1.

25 Like numerals of reference designate corresponding parts in all the figures of the drawings.

30 1 and 2 designate rods extending transversely of a wagon body or box 3 and provided at their outer ends with hooks 4 and 5, which engage eyebolts 6 of the sides 7 of the body or box. The sides 7 of the wagon body or box 35 are provided at their inner faces with vertical cleats 8, which are spaced apart to receive the ends of an end-gate 9 in the usual manner.

40 The inner ends of the transverse rods 1 and 2 are connected with an operating-lever 10, being secured in a bifurcation 11 of the same. One end of the operating-lever 10 is shaped to form a handle and its other end has the said bifurcation 11 and it is fulcrumed on a pivot 12, which passes through the bifurcated 45 portion and secures the lever to the outer face of the end-gate.

45 The rod 1 is provided at its inner end with

an eye 13, which is arranged on the pin 12^a of the operating-lever, and the outer portion of the rod 1 is connected with the handle portion of the lever by a link 14, provided at its ends with eyes, the lower one receiving the rod 1 and the upper one engaging a perforation of the operating-lever. When the operating-lever is swung upward, it carries the 55 hook 4 with it and lifts the same out of engagement with the eyebolt of the adjacent side of the body or box. The inner end of the other rod 2 is provided with an eye 14 and is secured to the operating-lever at the inner 60 side of the pivot 12 by a pivot or pin 16, which permits the rod to swing independently of the movement of the lever. When the operating-lever is swung upward, the rod 2 is simultaneously moved in the same direction to disengage it from the eyebolt by means of a lever 65 17, fulcrumed between its ends at 18 on the end-gate at a point beneath the rod 2 and the bifurcated end of the operating-lever and connected with those parts by substantially 70 vertical rods 19 and 20. The rod 19, which is connected at its lower end with the outer end of the lever 17, has its upper portion guided in an eye 21 and is provided at its upper terminal with an eye 22, which receives 75 the rod 2. The lower end of the vertical rod 19 is provided with an eye which is linked into a corresponding eye of the lever 17; but the connection may be made by a pivot or any other suitable means.

80 The rod 20 is provided at its lower end with an eye to engage a perforation or eye of the inner end of the lever 17, and its upper end is provided with an eye and is secured by a pivot 23 to the operating-lever at the outer 85 end of the bifurcation. When the bifurcated end of the operating-lever is moved downward, the rod 20, which is located at the outer side of the pivot 11, is carried downward, and this movement, through the lever 17, effects an upward movement of the rod 19, whereby when the operating-lever is raised the hooks will be simultaneously disengaged 90 from the eyebolts. A downward movement of the handle portion of the operating-lever 95 carries the hooks into engagement with the eyebolts, and as the inner ends of the transverse rods 1 and 2 are pivoted to the operating-lever at opposite sides of the fulcrum- 100

point thereof the locking action of the lever operates to draw the rods inward, thereby tightly binding the sides of the wagon body or box against the ends of the end-gate and effectually preventing them from becoming loose or spreading. By this construction, together with the adjustment afforded by the eyebolts, the end-gate fastener is adapted to take up the wear of the parts and hold the wagon body or box firmly together.

The invention has the following advantages: The end-gate fastener, while being exceedingly simple and inexpensive in construction, dispenses with a continuous transverse rod and is adapted to bind the sides of a wagon body or box firmly against the ends of an end-gate and prevent them from spreading. The device is also adapted to take up the wear of the parts and prevent them from becoming loose. It is easily operated, and by simply lifting the handle end of the operating-lever both hooks are simultaneously disengaged from the eyebolts of the sides of the wagon-body and the end-gate is released. Changes in the form, proportion, and minor details of construction may be resorted to without departing from the spirit or sacrificing any of the advantages of this invention.

What I claim is—

1. An end-gate fastener comprising an operating-lever designed to be fulcrumed on an end-gate and carrying a hook adapted to engage one side of a wagon-body, a rod pivotally connected with the operating-lever and adapted to engage the other side of the wagon-body, a lever 17 fulcrumed between its ends and located at a point below the operating-lever and the rod, and rods connecting the ends of the lever 17 with the operating-lever

and said rod, whereby when the operating-lever is swung upward, its hook and the rod will be simultaneously disengaged from the sides of the wagon-body, substantially as described. 40

2. An end-gate fastener comprising an operating-lever designed to be fulcrumed on an end-gate, transverse rods connected at their inner ends with the operating-lever and adapted to engage the sides of a wagon-body, connections between the outer portion of one of the rods and the operating-lever, the lever 17 fulcrumed between its ends, and rods connecting the lever 17 with the other rod and with the operating-lever, substantially as described. 45 50

3. The combination with a wagon-body provided at opposite sides with eyes, an end-gate, an operating-lever fulcrumed near one end on the end-gate, rods 1 and 2 connected at their inner ends to the operating-lever and provided at their outer ends with hooks engaging said eyes, a link connecting the handle end of the operating-lever with the rod 1, a guide-eye mounted on the end-gate, the lever 17 fulcrumed on the end-gate below the operating-lever, the rod 19 connected with one end of the lever 17, passing through the guide-eye and arranged to lift the rod 2, and the rod 20 connecting the operating-lever with the lever 17, substantially as described. 55 60 65 70

In testimony that I claim the foregoing as my own I have hereto affixed my signature in the presence of two witnesses.

M. T. KOCH.
